UNITED STATES PATENT OFFICE

WILLIAM H. BARNARD, OF MERCHANTVILLE, NEW JERSEY.

VULCANIZER.

No. 892,209.

Specification of Letters Patent. Patented June 30, 1908.

Application filed January 16, 1906. Serial No. 296,265.

To all whom it may concern:

Be it known that I, WILLIAM H. BARNARD, of Merchantville, in the State of New Jersey, have invented certain new and useful Improvements in Vulcanizers, whereof the following is a specification, reference being had to the accompanying drawings.

It is the object of my invention to provide a machine arranged to vulcanize rubber hose by utilizing a supply of steam within the hose.

My invention comprises a drum having a channel upon its periphery, and a casing removably fitted to said drum and having a channel complementary to the channel in said drum. As hereinafter described, such a drum is conveniently provided with axially aligned trunnions projecting at its opposite ends, upon which it may be rotated to facilitate the winding and unwinding of the hose with respect to said channel which extends spirally upon the periphery of the drum; said hose being connected with a steam supply pipe, exterior to said drum.

My invention also includes the provision of a steam chamber within the drum, and a steam chamber within the casing, having suitable steam supply connections and arranged to supplement the heating effect of the steam within the hose and maintain the proper temperature during the vulcanizing operation.

The ordinary vulcanizers heretofore employed being of such construction as to be limited to the treatment of short lengths of hose (for instance 50 feet) which must be jointed to form a greater length; the present invention is advantageous in that it permits of the manufacture of any desired length (for instance 500 feet) of vulcanized hose, without joints.

My invention comprises the various novel features of construction and arrangement hereinafter more definitely specified.

In the accompanying drawings, Figure I, is a plan view of a vulcanizer conveniently embodying my improvements. Fig. II, is a sectional view taken on the line II, II, in Figs. I, and III. Fig. III, is a sectional view taken on the line III, III, in Figs. I and II. Fig. IV, is a plan view of a modified form of vulcanizer embodying my improvements, the upper section of the casing being removed. Fig. V, is a sectional view of said vulcanizer, taken on the line V, V, in Figs. IV and VI. Fig. VI, is a sectional

view of said vulcanizer, taken on the line VI, VI, in Figs. IV and V.

Referring to the form of my invention shown in Figs. I, II, and III; the lower casing section or base 1 is provided with the flanges 2, at opposite sides of the semi-cylindrical concavity 3, slotted to receive the lugs 4, which extend through the flanges 7, on opposite sides of the concavity 8, in the upper casing section or top 10, which latter is provided with the eye-bolt 11, by which it may be removed when desired. The drum 14, is fitted to the semi-cylindrical recesses 3, and 8, in said casing and has the spiral channel 15, upon its periphery, complementary to the spiral channels 16, in the casing. Said channels are provided at opposite ends of the drum with sockets 17, and 18, through which the ends of the hose 19, extend for connection with a steam supply conveniently directed therethrough by the conduits 23, and 21. The periphery of said drum 14, is connected by the webs 24, and 25, with the hub 26, having trunnions 28, and 29, projecting at opposite ends thereof in axial alinement. As shown in Fig. II, said drum 14, is provided with oppositely extending lugs 32, which carry dowel pins 33, secured by the nuts 34, in screw threaded engagement with their inner ends, and fitted to the sockets 36, in the casing base 1. Said sockets are conveniently provided with bushings 37, which may be renewed when worn.

As indicated in Fig. I, the casing top section 10, is conveniently provided with lugs 38, in which are fitted dowel pins 39, which are also fitted in the flanges 2, on the lower casing section 1, so as to insure the proper registration of said casing sections.

The vulcanizer above described may be operated as follows: The drum 14, being removed from the casing may be conveniently rotated upon its trunnions 28, and 29, while a sufficient length of hose 19, is wound thereon in the spiral channel 15. Said drum 14, is then lowered into the recess 3, in the casing base section 1, as indicated in Figs. II, and III; the alinement of the channels 15, and 16, to form a continuous cylindrical receptacle for the hose 19, being assured by the registration of the dowel pins 33, in the socket bushings 37. Thereupon, the casing top section 10, is lowered, conveniently by its eye bolt 11, into the position shown in Figs. II, and III, the proper registration of the chan-

nels 16, in said section 10, with the channels 15, in the drum, being assured by the registration of the dowel pins 39, in their sockets. The bolts 4, are then inserted in the notches 5 in the flanges 2, and 7, and the two sections of the casing clamped together as indicated in Fig. III. Thereupon, the conduits 20, and 21, are fitted to the projecting ends of the hose 19, and a supply of steam is directed 10 through said conduits and through the hose 19, for such a length of time and at such a temperature as to vulcanize the latter. In order to remove the hose 19, it is of course necessary to reverse the assembling operation 15 above described, and, the drum 14, being mounted upon its trunnions 28, and 29, may be conveniently rotated to unwind the hose 19.

In the form of my invention shown in Figs. IV, V, and VI; the lower casing section or 20 base 41, comprises the internal steam chamber 42, provided with the inlet 43, and outlet 44. Said base 41, has the flanges 45, at opposite sides of the semi-cylindrical concavity 46, provided with the dowel pins 47, secured 25 by the nuts 48, and fitted to the sockets 49, in the flanges 50, on opposite sides of the concavity 51, in the upper casing section or top 53. Said casing section 53, comprises the internal steam chamber 54, having the 30 inlet 55, and outlet 56, and is provided with the eye-bolts 57, by which it may be removed when desired. The drum 60, is fitted to the semi-cylindrical concavities 46, and 51, in 35 said casing and has the spiral channel 63, upon its periphery, complementary to the spiral channels 64, in the casing. Said channels are provided at opposite ends of said drum 60, with sockets 66, and 67, through 40 which the ends of the hose 68, extend for connection with a steam supply conveniently directed therethrough by the conduits 69, and 70. The periphery of said drum 60, is connected with the hubs 74, by the imperforate webs 75, on opposite ends of 45 the drum, inclosing the steam chamber 76, having the steam inlet 78, outlet 79, and drip pipe 80. Said drum 60, is conveniently provided with trunnions 85, and 86, projecting at opposite ends thereof in axial alignment. Said drum 60, is provided with oppositely extending lugs 88, (shown in Figs. IV, and V,) comprising sockets 89, in which are fitted the dowel pins 91, which are secured 50 by the nuts 92, in screw threaded engagement with the casing base section 41. It is to be understood that the hose 68, may be wound upon and removed from the drum 60, in the same manner as described with respect to the drum 14.

60 It may be noted that the construction last described, with reference to Figs. IV, V, and VI, is similar to that described with reference to Figs. I, II, and III, except that the former comprises chambers 42, 54, and 76, which 65 may be charged with steam to supplement

the heating action of the steam within the hose 68, which is to be vulcanized, in the complementary channels 63, and 64, whereas, in the form first described, heat for the vulcanizing operation is derived solely from 70 the steam directed through the hose 19, which is to be vulcanized.

It is to be understood that I do not desire to limit myself to the precise details of construction and arrangement herein set forth, 75 as various modifications may be made therein without departing from the essential features of my invention.

I claim:—

1. In a vulcanizer, the combination with a 80 drum having a spiral channel on its periphery having terminal sockets opening at the ends of said drum; of a casing comprising a spiral channel having terminal sockets opening at the ends of said casing complementary 85 to the channel in said drum and forming therewith a receptacle for the tube to be vulcanized; and, means arranged to direct a steam supply through said tube, substantially as set forth.

2. In a vulcanizer, the combination with a 90 drum having a spiral channel on its periphery having terminal sockets opening at the ends of said drum; of a casing comprising separable sections and having a spiral groove 95 having terminal sockets opening at the ends of said casing complementary to the groove in said drum and forming therewith a receptacle for the tube to be vulcanized; and means arranged to connect said tube with a 100 steam supply, substantially as set forth.

3. In a vulcanizer, the combination with a 105 drum, having spiral channels on its periphery having terminal sockets opening at the ends of said drum; of a casing comprising 110 separable sections each comprising an internal steam chamber, and having a spiral groove having terminal sockets opening at the ends of said casing complementary to the groove in said drum, and forming therewith a receptacle for the tube to be vulcanized; and, means arranged to connect said chamber and said tube with a steam supply, substantially as set forth.

4. In a vulcanizer, the combination with a 115 casing base comprising a spirally channeled semi-cylindrical concavity; of a casing top comprising a semi-cylindrical concavity having spiral channels complementary to the channels in said base; a spirally channeled 120 drum fitted to the concavities in said casing base and top; means arranged to prevent the rotation of said base; and, means arranged to removably secure said casing and drum in operative relation, substantially as set forth.

5. In a vulcanizer, the combination with a 125 drum having a spiral channel on its periphery and axially projecting imperforate trunnions upon its opposite ends; of a casing comprising a spiral channel complementary to the 130

- channel in said drum, and forming there-
with a receptacle for the tube to be vul-
canized; and, means arranged to removably
secure said casing and drum in operative re-
lation, substantially as set forth.
6. In a vulcanizer, the combination with a
drum having a channel on its periphery hav-
ing terminal sockets opening at the ends of
said drum; of a casing comprising a channel
complementary to the channel in said drum
and forming therewith a receptacle for the
tube to be vulcanized; and, means ar-
ranged to direct a steam supply through said
tube, substantially as set forth.
- 10 7. In a vulcanizer, the combination with a
drum having a channel on its periphery hav-
ing terminal sockets opening at the ends of
said drum; of a casing inclosing said drum

and having a groove complementary to the
groove in said drum and forming therewith a 20
receptacle for the tube to be vulcanized; and,
means arranged to connect said tube with a
steam supply, substantially as set forth.

8. In a vulcanizer, the combination with a
drum arranged to support a tube to be vul- 25
canized and having sockets for said tube at
the ends of said drum; and means arranged to
connect said tube with a steam supply, sub-
stantially as set forth.

In testimony whereof, I have hereunto 30
signed my name, at Philadelphia, Pennsyl-
vania, this 26th day of December, 1905.

WILLIAM H. BARNARD.
